UNITED STATES PATENT OFFICE.

JOHN P. THOMAS, OF CHICAGO, ILLINOIS.

ARCH-SUPPORTER.

1,073,708.

Specification of Letters Patent. Patented Nov. 18, 1913.

Application filed June 6, 1912. Serial No. 701,986.

To all whom it may concern:

Be it known that I, JOHN P. THOMAS, a citizen of the United States, residing at Chicago, in the county of Cook and State of Illinois, have invented certain new and useful Improvements in Arch-Supporters, of which the following is a specification.

This invention relates to improvements in arch supporters, and refers more particularly to improvements in removable arch supporters intended to be fitted within previously or separately made shoes.

The salient object of the present invention is the usual one aimed at in devices of this character, viz: to provide an arch supporter which will so support the instep or arch portion of the foot of the wearer, especially one whose feet have become deformed or, as it is commonly called, broken down, that he will be afforded relief and his foot comfortably supported in, or approximately in, its natural or normal position.

I am aware that the prior art shows many examples of arch supporters, and several of these appear upon cursory examination to be quite closely analogous to the arch supporter of my present invention. However, as will appear from the following description, my arch supporter is constructed to embody a different principle of operation from those heretofore devised, so far as my present knowledge goes, and in practice has proved highly successful and to be constructed in accordance with correct and sound principles, so that it not only affords immediate but also permanent relief and the wearer is not compelled to endure a more or less extended period of "breaking-in" discomfort.

In devising the arch supporter of my present invention, I have proceeded, upon the theory or understanding that such a device in order to be at the same time comfortable and efficient must be so constructed as to accommodate itself very exactly to the irregularities of the foot of the wearer; must possess a certain amount of permanent resiliency or cushioning characteristics; must be of such shape as to be thickest and afford

greatest support throughout the middle part 50 of the arch, and above all must be so organized as to exercise its corrective effects gradually, so that the foot of the wearer may be restored to its correct or normal shape by successive stages and so gradually as to be 55 accomplished without pain and discomfort. In this respect the arch of my present invention follows the same principle as that followed by the dentist in correcting crooked or deformed teeth, viz: by using appliances 60 which will direct the tooth to the desired position so gently and gradually that the tooth simply grows away from the acting pressure and the change is accomplished without pain. 65

The device of my invention is also designed and intended to be of a prophylactic nature; that is, to be beneficially worn not only by persons already suffering from breaking down of the arch, but also by persons who may exhibit a tendency in that direction. In this character, the device is useful not only as preventing breaking down of the arch with its concomitant evils, but also in preventing the formation of corns 75 and callous parts on the heel and ball of the foot, as well as restoring and maintaining normal blood circulation.

Describing, now, the device shown in the drawing, which shows the preferred embodiment, 1 designates as a whole the foundation layer or piece, which consists of a piece of firm, smooth leather, intermediate in pliability and stiffness between ordinary sole leather and ordinary shoe-upper leather, 80 having its margins shaped to outline a heel portion 1' formed to substantially fit the heel area of a shoe of that size for which it is intended, the front end portion 1" wide enough to substantially occupy the sole area 85 across the ball or widest part of the shoe; and an outwardly curved portion 1" between the heel and front portions and at the inner side of the arch, forming when in position in the shoe an upturned wing-like 90 arch support. The margin of 1" of the member 1, is curved inward slightly and is intended to conform to the internal shape of

the shoe; that part of the arch supporter being intended to rest flat, or substantially so, when in use.

The member 1 is intended to lie next to the foot of the wearer. Upon the under side of said member 1 are arranged a plurality of layers of soft pliable leather, or other suitable material, of successively smaller area, and of such outline as to approximately 5 form to the outline of the main or foundation piece 1. These successive layers, designated 2, 3, and 4 in the drawing, desirably have their marginal portions skived thin so as to produce a pad increasing in thickness 10 with substantial uniformity from the outer margin of the largest piece 2 to the center of the smaller piece 4, and the several layers are secured together and to the foundation member 1 by any suitable impaling means 15 which engages the central portions of said members only. Preferably I employ a split rivet 5, the head of which is very thin, smooth and the two shanks of which extend through the superposed portions of leather 20 through the superposed portions of leather 25 and are clenched upon the latter, as shown clearly in Fig. 3.

The members of the support thus far described form a pad-like structure possessing considerable pliability but comparatively little resilience or cushioning qualities. To impart to the device as a whole a pronounced cushioning quality, I superpose upon the built-up leather pad a covering of substantial thickness of some permanently 30 elastic fabricated material which will retain its structure permanently, such for example as wool felt or flannel. Preferably the covering is composed of a plurality of layers so that the central portion may be made thick- 35 est and the margins uniformly thinner. To this end, in the construction shown, I provide a plurality of layers of felt or flannel, designated 6, 7 and 8, and since the member 6 will lie next to the outer leather covering, 40 I prefer to make this member of substantially the full area of the pad and the underneath layers, as 7 and 8, of graduated smaller area, as shown. Outside of the composite pad thus built up of leather and cushioning material I apply a covering 9 of very 45 soft leather, as for example sheepskin, which is shaped to conform to the marginal outline of the foundation piece 1 (except that it is shorter at the forward end, as indicated), 50 and the leather covering 9 and the foundation piece 1 are stitched together by a marginal seam 10, as shown clearly in the drawing. The front end of the foundation piece 1 outside of or beyond the corresponding 55 margin of the pad proper is preferably skived to a thin edge, as indicated clearly at 60 11, Fig. 4, so that there will be no abrupt ridge or shoulder between the forward end 65 of the pad and the sole of the shoe. The

layers 6, 7 and 8 are entirely free from positive connection with each other and with the various other layers and the member 1 and cover 9 and free to expand, contract and shift locally to adapt the supporter to the contour of the foot. Without such soft layers the supporter might not fully conform 70 with the contour of the foot and might exert uncomfortable local pressures, but the soft felt-like layers will yield and shift under such local pressures on the upper part of 75 the structure and will thus eliminate such local pressures against the foot.

It will be noted that in the device of my invention the cushioning effect is extended into the heel portion of the support, and is 80 not limited to the instep portion alone, as is usually the case in articles of this character.

While I have herein described a preferred embodiment of the invention which I have found extremely successful and satisfactory 85 in use, it will nevertheless be obvious that some variation may be made in the details of construction without departing from the invention.

I claim as my invention:

1. A removable arch supporter, comprising a composite cushion comprising a foundation-piece of firm smooth leather intermediate in pliability and stiffness between ordinary sole leather and ordinary shoe- 90 upper leather, having a heel portion formed to substantially fit the heel area of a shoe, a front end portion wide enough to substantially occupy the sole area across the ball or widest part of the shoe, an outwardly curved 95 portion between the heel and front portions and at the inner side of the arch, forming when in position in the shoe an upturned wing-like arch support, a plurality of layers 100 of softer and more flexible material of successively smaller areas below the first mentioned layer and united therewith by impaling means extending through the central portions only of the several layers, soft permanently elastic cushioning material below 105 said previously described layers, and a covering of very soft leather having its margins joined in the margins of the main layer and fully inclosing the other layers.

2. In a removable arch supporter, the 110 combination with a composite pad comprising a foundation piece of firm smooth leather having a heel portion formed to substantially fit the heel area of a shoe, a front 115 end portion wide enough to substantially 120 occupy the sole area across the ball of the shoe, an outwardly and upwardly curved portion between the heel and front portions and at the inner side of the arch, a plurality 125 of layers of thinner and more flexible leather of successively smaller area below said foundation piece and united thereto by means extending through the central portions only

of the several layers, of a plurality of permanently elastic layers of flannel-like material below said previously described layers, and a covering of very soft leather having its margins joined to the margins of the foundation piece to fully inclose the other layers, said permanently elastic layers being free from positive connection with each

other and with the other layers and the covering and thus free to expand and contract 10 and to shift locally to adapt the supporter to the foot.

JOHN P. THOMAS.
